SEALING MEANS FOR CARTONS

Manuel G. Rodriguez, New York, N. Y.

Application April 17, 1947, Serial No. 742,173

12 Claims. (Cl. 229—45)

1

This invention relates to an improved sealing means for cellular cartons such as are used to package eggs or other generally similar articles for retail sale.

This improved sealing means is designed to be used with egg cartons of the general type disclosed by Reissue Patents Nos. 19,250 and 19,143, in which individual cells are provided for the eggs. In such cartons the individual cells are formed by a longitudinally-extending, central, vertical partition, and a series of transversely-extending, longitudinally-spaced partitions which extend through slots in the bottom wall of the carton and are themselves slotted to receive the longitudinally-extending partition. These transversely-extending partitions are freely removable from the carton by merely pulling them out through the slots in the bottom of the carton. Because of this construction, the contents of the box may be tampered with, even though the top is sealed, by merely removing these transversely-extending partitions.

More specifically the invention contemplates the insertion of a sealing tape or string through the vertical partitions of the carton to secure them to the body of the carton so that they cannot be removed. This will prevent tampering with the contents of the carton.

The invention will be further described in connection with the accompanying drawings in which:

Fig. 1 is a top plan view of an egg carton embodying the sealing means of the present invention, with one side thereof being shown open, prior to its sealing.

Fig. 2 is a transverse sectional view through the central portion of the carton.

Fig. 3 is a longitudinal sectional view through one end of the carton, the same being taken on line 3—3 of Fig. 2.

Fig. 4 is a perspective view of one end of a carton showing a modified form of sealing means.

Fig. 5 is a perspective view of one end of a carton showing a further modification of the sealing means.

Fig. 6 is a perspective view of one end of a carton showing a still further modification of the sealing means.

Fig. 7 is a longitudinal sectional view of a carton showing another form of sealing means, and

Fig. 8 is a longitudinal sectional view of a carton embodying a still further modification of the sealing means.

As disclosed in the aforesaid residue patents,

2

the carton is formed from a blank which is folded along a longitudinal center line and upon itself to form a longitudinally-extending partition 1 which divides the carton, longitudinally, into two sections. The blank also is folded longitudinally to form bottom walls 2 and 2', side walls 3 and 3', top or cover walls 4 and 4', and tuck-in flaps 5 and 5', for each section.

The bottom walls are provided with a series of transverse, longitudinally-spaced slots 6 through which cross partitions 7 are inserted, to form with the central longitudinal partition, a series of cells for the reception of eggs or the like. The cross partitions are formed with slots 8 extending inwardly from their upper edges for receiving the longitudinally-extending partition and the tuck-in flaps 5 and 5', as shown in Fig. 2. At one side the slots 8 are widened at the entrance ends to facilitate insertion of the tuck-in flaps.

Cartons constructed as set forth above have been extensively used. However, as the cross partitions 7 have merely been held in place by friction, it has been possible to readily withdraw them from the bottom of the box, even though a sealing tape or the like has been secured across the two top or cover walls 4 and 4'. Hence it has been possible for an unscrupulous person to tamper with the contents of the carton without in any way disturbing a seal placed across the top.

In order to prevent withdrawal of the cross partitions 7, and consequently tampering with the contents of the carton, each cross partition 7 of the carton shown in Figs. 1 to 3 is formed with slots 9 and 9' in those portions thereof which lie just inwardly of the bottom walls 2 and 2'. Sealing tapes 10 and 10' of paper, cellophane, or the like, or in some instances cords, are threaded through the several slots 9 and 9' and, when the cells are filled, lie against the bottom walls 2 and 2'. The sealing tapes extend upwardly along and are secured by adhesive or otherwise to the outer sides of the cross partitions 7 at the ends of the carton. The tapes then are threaded through slots 11 and 11' formed in the portions of the top or cover walls 4 and 4' which extend beyond the cross partitions, and their ends overlapped at the top of the container and adhesively or otherwise secured together. Thus the tapes function as locking or sealing means to prevent withdrawal of the cross partitions 7 through the slots in the bottom walls and removal of the contents

through the open ends of the sections at opposite sides of the longitudinal partition 1.

The sealing means for the carton shown in Fig. 4 is identical in all respects to the sealing means for the carton of Figs. 1 to 3, except that the end portions of each sealing tape 28, instead of extending entirely along the top or cover wall 24 of the carton and being secured to one another where they overlap, are secured by adhesive, staples or otherwise directly to the outer surface of the end portions of the closed top or cover walls of the carton.

In Fig. 5 a carton is shown in which the sealing means is identical with the sealing means shown in Fig. 4, except that just inwardly from the place where the end portions of the tapes 30 are adhesively secured to the outer surface of the top or cover wall 34, that wall is provided with slots 32 through which the ends of the tapes are passed to lie within the carton.

Instead of applying adhesive to the underside of the ends of the tapes which overlie the top of the carton for adhesively securing them to the carton, as shown in Figs. 4 and 5, a seal 39 may be placed over the ends of the tapes 40 and 40' and secured to them and to the top of the carton, as shown in Fig. 6. In all other respects the sealing means in this form of the invention is the same as the sealing means of the preceding forms of the invention.

In Fig. 7 I have shown sealing means which differs from the sealing means of the embodiment of the invention shown in Fig. 5 in that the slots 53 and 53' in the top wall or cover 52 are located nearer to the longitudinal center of the carton, and the cross partitions 57 and 57' at the end of the carton are formed with slots 53 and 53' through which the tapes are threaded from the outer ends of the cartons. After being threaded inwardly through the slots 53 and 53', the tapes pass over the cells at each end of the carton and then upwardly and outwardly through the slots 53 and 53' and are adhesively secured to the outer surface of the top or cover walls 52. The ends of the tapes then are passed downwardly and inwardly through slots 54 so as to lie inside the carton. If desired, the slots 54 may not be provided and the ends of the tapes caused to overlap and be secured to one another, or to one another and to the outer surface of the top wall or cover 52, as in the manner shown in Figs. 1 and 4, respectively.

The form of the invention shown in Fig. 8 embodies the basic idea of utilizing sealing tapes to prevent removal of the cross partitions. However, instead of the slots 69 being formed in the cross partitions 67 near their lower edges as in the preceding forms of the invention, they are formed near the upper edges of the partitions. The sealing tapes 70 are threaded through the slots 69 and then doubled back upon themselves above the upper edges of the cross partitions and the ends overlapped and adhesively or otherwise secured together. If any attempt should be made to withdraw the cross partitions through the bottom of the carton, after the cells thereof have been filled with eggs or other similar articles, the tapes will bind against the top of the eggs and thereby prevent withdrawal of the partitions.

In all forms of the invention, except the form shown in Fig. 8, the free ends of the sealing tapes will be secured to one another or to the outer surface of the top or cover wall of the carton after the carton has been filled and closed. In the embodiment disclosed in Fig. 8, the ends of the tapes

will be secured to one another after the carton has been filled, but before it has been closed.

From the aforesaid it will be apparent that the present invention provides a very effective, yet inexpensive means of sealing or locking the cross partitions of egg and like cartons against withdrawal, and consequently prevents tampering with or removal of the contents of the carton.

Various changes may be made in the details of the invention without departing from the advantages thereof.

I claim:

1. A carton comprising confining walls, partitions constructed and arranged to form cells within the confining walls, at least some of the partitions extending into the carton through slots in one of the confining walls, said last-named partitions having openings in them within the carton, and a separate sealing strip extending through said openings and secured against removal.

2. A carton as set forth in claim 1 in which the sealing strip is secured against removal by having the end portions thereof attached to a part of the carton.

3. A carton comprising confining walls, partitions constructed and arranged to form cells within the confining walls, at least some of the partitions extending into the carton through slots in one of the confining walls, at least some of the partitions and one of the confining walls having openings in them, the openings in said partitions being within the carton, and a separate sealing strip extending through the openings in said partitions and in said confining wall and being secured against removal.

4. A carton as set forth in claim 3 in which the sealing strip is secured against removal by being attached to the outside of the confining wall having the openings therein.

5. A carton as set forth in claim 3 in which the sealing strip is secured against removal by having the ends thereof secured together.

6. A carton comprising confining walls, partitions constructed and arranged to form cells within the confining walls, at least one longitudinally-extending partition, a series of transverse, longitudinally-spaced cross partitions, said partitions cooperating to form cells within the carton, one of the confining walls extending beyond the cross partitions at the ends of the carton, said one of the confining walls having an opening in the extending portion at each end thereof, at least some of the cross partitions extending into the carton through slots in one of the confining walls and having openings in them within the carton and adjacent to one of the confining walls and a separate sealing strip extending through the openings in said cross partitions and said one of the confining walls and secured against removal.

7. A carton as set forth in claim 6 in which the sealing strip is secured against removal by being attached to the outer surface of said one of the confining walls.

8. A carton as set forth in claim 6 in which the sealing strip is secured against removal by having the ends thereof secured to one another.

9. A carton as set forth in claim 1 in which the openings in the partitions are in the upper portions of the partitions and in which the sealing strip after extending through said openings extends back over the upper edges of said partitions and has its end secured together.

10. A carton as set forth in claim 6 in which

the sealing strip is secured to the outer surface of said one of the confining walls, and said one of the confining walls is provided with at least one additional slot, and the sealing strip, after being secured to said outer surface, is passed through said slot to the inside of the carton.

11. A carton comprising confining walls, at least one longitudinally-extending partition, and intermediate transverse partitions, said partitions being constructed and arranged to form cells, said transverse partitions extending through slots in one of the confining walls, each of said transverse partitions having a slot just inwardly from said confining wall and the end transverse partitions each having an additional slot near their inner edges, the confining wall lying adjacent the inner edges of said transverse partitions having a pair of slots therein, inwardly from said end partitions, and a sealing strip extending through the first-mentioned openings in the transverse partitions, upwardly along the outside of said end partitions, through the second-mentioned openings in said end partitions and the openings in the confining wall adjacent the inner edge of said end partitions and secured against removal between said two openings in said confining wall.

12. A carton comprising confining walls, partitions constructed and arranged to form cells within the confining walls, at least some of the partitions extending into the carton through slots in one of the confining walls, said last-named partitions having openings in them within the carton, and a separate sealing member extending through said openings and holding said partitions against removal.

MANUEL G. RODRIGUEZ.
